UNITED STATES PATENT OFFICE.

CHARLES J. STROSACKER AND HOWARD J. RUPRIGHT, OF MIDLAND, MICHIGAN, ASSIGNEES TO THE DOW CHEMICAL COMPANY, OF MIDLAND, MICHIGAN, A CORPORATION OF MICHIGAN.

METHOD OF MAKING BROMINATED INDIGOS.

No Drawing. Application filed December 13, 1918. Serial No. 220,262.

To all whom it may concern:

Be it known that we, CHARLES J. STROSACKER and HOWARD J. RUPRIGHT, citizens of the United States, and residents of Midland, county of Midland, State of Michigan, have jointly invented a new and useful Improvement in Methods of Making Brominated Indigos, of which the following is a specification, the principle of the invention being herein explained and the best mode in which we have contemplated applying that principle, so as to distinguish it from other inventions.

The bromination of indigo, especially where the higher bromine substituted products are desired, has apparently been heretofore regarded as presenting peculiar difficulties. Furthermore, the highest number of bromine atoms that have been thus substituted in the benzene nuclei has been six. In view of the reported difficulties in brominating indigo to obtain the higher derivatives, necessitating the use of particular diluents or vehicles in which to carry on the reaction between the original indigo and the bromine as well as the use of elevated temperatures or pressures or both, our present discovery is indeed surprising since we have found it possible to directly react on dry indigo with bromine at atmospheric pressure and at a temperature not above 80 degrees centigrade. Where a diluent, as hereinafter explained, is employed, the reaction may be carried on in ordinary iron instead of enameled vessels. By the simple procedure which is outlined, we have furthermore been successful in obtaining two higher bromindigos, which so far as we are aware have never heretofore been produced, namely, hepta-brom indigo and octo-brom indigo, respectively containing seven and eight atoms of bromine attached to the benzene nuclei.

To the accomplishment of the objects thus indicated, the invention, then, consists of the steps hereinafter fully described and

particularly pointed out in the claims, the following description setting forth merely certain steps which may be employed.

As previously indicated, we use dry indigo as the starting material for producing the several bromine substitution products. The latter we have found may be produced by allowing varying amounts of bromine to act directly on such dry indigo, either with or without the presence of an inert diluent, namely carbon tetrachloride, the reaction being conducted at a temperature of from 70 degrees to 80 degrees centigrade, under atmospheric pressure. The reaction requires to be continued for some hours, the period being longer where it is desired to produce the higher bromine compounds indicated above. The amount of bromine employed will be somewhat in excess of the theoretical required to form the desired substitution product whether the latter be mono-brom, tetra-brom, penta-brom, hexa-brom, hepta-brom or octo-brom indigo. For producing the lower range of derivatives just enumerated, e. g. up to tetra-brom indigo, an excess of from 15 to 25 per cent of bromine will be sufficient, while for producing the hepta-brom or octo-brom indigo, this excess should be somewhat higher, e. g. 50 to 60 per cent.

The dry indigo with the proper amount of liquid bromine, is placed in a suitable enameled reaction chamber provided with stirring means and held in such chamber with constant stirring at a temperature of from 70 to 80 degrees, but under atmospheric pressure, until such time as the bromination is complete, as may be determined by analysis. For producing the higher derivatives the reaction may require to be continued for ten or twelve hours or upwards. It will be also understood that by stopping the bromination at an intermediate stage a mixture of higher and lower bromine derivatives will be obtained. Such a product is not necessarily undesirable since,

as is well known, various commercial brands of indigo have consisted of mixtures of different bromine substitution products.

Carbon tetrachloride may be advantageously utilized as a diluent or vehicle in which to conduct the reaction, especially since we have found that the bromine will in such case attack the iron to a much less extent, so that the reaction can be carried out in an ordinary iron reaction chamber. The preferred form of apparatus in such case is an ordinary tumbler consisting of a cylindrical drum rotatable about its axis and containing a quantity of iron balls which grind the indigo at the same time that they keep it and the bromine which is dissolved in the tetrachloride in thorough and constantly changing contact. Such drum will of course be jacketed to permit the temperature to be properly controlled.

In either case the bromine which has not entered into reaction is distilled off or otherwise separated from the mass of indigo derivative, and the latter thereupon treated with a bisulphite solution in order to remove that part of the bromine which is attached elsewhere than to the benzene nuclei. The resulting brominated indigo, whether in paste or powder (i. e. dry) form, presents much the appearance of ordinary indigo paste or powder except that a progressive change in color from the deep blue of pure indigo to a reddish purple is observable in passing from the lower to the higher bromine derivates. In other words, the mono-brom and dibrom indigo differ but little to all outward appearance from indigo, while the octo-brom indigo possesses a deep reddish purple towards which the intermediate products, e. g. penta-brom, hexa-brom and hepta-brom indigos successively more closely approach.

The constitution of the several brominated indigos, the two higher members of which (now obtained for the first time) complete the series in so far as substitution in the benzene nuclei is possible, has been found

upon analysis to correspond very closely with the theoretical, as indicated by the following table, viz:—

Mono-brom indigo	23.46 %	of bromine
Di-brom indigo	38.0 %	" "
Tri-brom indigo	48.0 %	" "
Tetra-brom indigo	55.3 %	" "
Penta-brom indigo	60.88 %	" "
Hexa-brom indigo	65.18 %	" "
Hepta-brom indigo	68.71 %	" "
Octo-brom indigo	71.5 %	" "

Other modes of applying the principle of our invention may be employed instead of the one explained, change being made as regards the method herein disclosed, provided the steps stated by any of the following claims or the equivalent of such stated steps be employed.

We therefore particularly point out and distinctly claim as our invention:—

1. The method of brominating indigo, which consists in reacting directly on the same dry with bromine in amount from 15% to 25% in excess of the theoretical to form the desired substitution product, the reaction being carried on at a temperature of from 70° to 80° C. and under atmospheric pressure.

2. The method of brominating indigo, which consists in grinding the same in dry form in a body of carbon tetrachloride to which has been added the requisite amount of bromine, substantially as described.

3. The method of brominating indigo, which consists in reacting directly on the same dry, in the presence of carbon tetrachloride, with bromine in amount from 15 per cent to 25 per cent in excess of the theoretical to form the desired substitution product, the reaction being carried on at a temperature of from 70° to 80° C. and under atmospheric pressure.

Signed by us, this 7th day of December, 1918.

CHARLES J. STROSACKER.
HOWARD J. RUPRIGHT.
